MACHINE FOR GRINDING OR POLISHING
CUTLERYAlbert Victor Hague, Jr., Crookes, Sheffield,
EnglandApplication September 7, 1932, Serial No. 632,016,
and in Great Britain July 23, 1931

5 Claims. (Cl. 51—122)

This invention relates to a machine for grinding or polishing cutlery and has for its object to provide efficient means whereby cutlery blades can be expeditiously ground or polished.

5 According to this invention a machine for grinding or polishing cutlery is so constructed that blades contact with the grinding wheel or polishing wheel for only one direction of radial or substantially radial movement relatively to such wheel.

In a convenient form of the invention a plurality of blade holders or carriers are mounted radially with respect to the grinding or polishing wheel and are adapted to be moved radially theretowards upon the end of a member which in turn is adapted to move axially with respect to the grinding or polishing wheel, the arrangement being such that the following cycle of movements occurs: alternate carriers are simultaneously brought inwards to bring the blades thereon into the field of operation of the wheel, the member moves forward to bring such blades at their bolster ends into contact with the radial face of the wheel, these carriers with the blades 20 thereon perform the radial movements. move outwards to effect the grinding or polishing, the member moves backwards to initial position and then the preceding movements are repeated but so that the remaining carriers with blades thereon perform the radial movements. It will be observed that the blades have no inward movement in contact with the grinding or polishing wheel.

Alternatively there may be the following cycle of movements; all the carriers are simultaneously brought inwards to bring the blades into the field of operation of the grinding or polishing wheel, the carriers move towards the wheel to bring blades at their bolster ends into contact with the radial face of the wheel, the carriers move outward to effect the grinding or polishing, they move away from the wheel to initial position, they are individually given a slight turn to bring a fresh set of blades opposite to the working face of the wheel, the preceding movements are repeated to grind or polish the fresh set of blades, and then the above cycle of movements is repeated until all the blades, say, nine, mounted about the periphery of the carriers have been ground or polished. In this way, as many blades as the number upon each carrier, say, nine, multiplied by the number of carriers, say, eight, or seventy-two, in all, can be quickly ground, and then the machine is stopped for the brief period necessary for a recharging of the carriers. With this alternative

arrangement also, the blades have no inward movement in contact with the working face of the wheel.

The action of the machine is automatic up to and including the stopping of the machine for unloading and recharging of the carriers.

The accompanying drawings show a convenient construction of machine made according to the present invention. In the said drawings, Figs. 1A, 1B and 1C give a complete view of the machine, Fig. 1A being a sectional elevation of one half of the upper portion, Fig. 1B being a side elevation of the other half of the upper portion and Fig. 1C being an elevation, partly in section, of the lower portion of the machine.

Fig. 2 shows an end elevation and section on the line 2—2 of Fig. 1A, looking in the direction of the arrow.

Fig. 3 shows a detail of parts shown in Fig. 2. 75

Fig. 4 shows a section on line 4—4 of Fig. 1A.

Fig. 5 is a detail view to an enlarged scale of an assembly shown in Fig. 1C.

Fig. 6 is a diagrammatic view of a modification.

Fig. 7 is a plan view of the machine showing four of the work carriers in their relation to the grinding wheel.

The wheel 1 is driven by means of a shaft 2 and pulley 3. Another pulley 4 affixed to the said shaft drives the fluid pump 5 by belt 5a and pulley 5b. Surrounding the shaft and causing it to be supported at both ends is a housing 6, attached to or in one with the base of the machine. Arranged concentrically around the housing 6 and slideable vertically is a sleeve 7 adapted to be moved axially with respect to the wheel. Attached to the face 7a of the sleeve 7 nearest to the wheel is a hub 8, which moves coaxially with the said sleeve 7. A number of piston rod guides 9 are fitted tightly in the hub in radial positions and obliquely with respect to the wheel 1. Stationary pistons 10 are situated at that end of the piston rod guides, hereinafter called guides, furthest away from the hub.

As many guides are provided as the circumference of the hub will permit, say eight. For simplicity's sake the drawings show a construction of machine with four guides only. 105

A cylinder 11 surrounding each guide is adapted to have a reciprocating and rotational or swivel movement about its guide, said cylinders having a bore 11a to suit the piston diameter and a bore 11b to suit the guide diameter; a 110

flanged leather 12 surrounds the guide at the inner end of the cylinder.

Racks 13, Figs. 1A, 1B, and 2, are longitudinal extensions from the cylinders at the side furthest away from the wheel. Engaging these racks are pinions 14 mounted on shafts 15, supported by bearings 16 and 17, forming part of extensions 7b from the sleeve 7. Shafts 15 are interconnected by means of universal joints 18, thereby effecting uniform and simultaneous reciprocation of the cylinders.

Means are provided for limiting the outward movement of the cylinder 11. As shown, a pin stop is inserted in one of a number of holes 19 in the face of the pinion 14, such pin engaging an adjustable stop 20 on the bearing extension 7b from sleeve 7.

The limit of inward movement of the cylinder 11 along the guide 9 is accomplished by the cap 21 engaging the outer face of piston 10.

Adjustable strips 22 and 23 Figs 1B and 2, are attached longitudinally at the side of each cylinder, said strips being inclinedly adjustable through the medium of slots 22a, screws 22b and set screws 22c, upon the surface of the cylinder. The strip 23 engages a roller 24 mounted in an upright arm 25 attached to the extension 7b from the sleeve 7, said roller thereby providing a reaction against the thrust of the wheel 1 upon the blade being ground or polished. The other strip 22 engages a roller 26 mounted at the end of a rod 27, said rod working slidably in an upright guide 28 against a spring 29, the guide being attached to the extension 7b from the sleeve 7.

The spring 29 acts upon the bottom end of the rod 27 causing the strip 23 to be held up to and against its corresponding roller 24.

As the cylinders move along their respective guides the strips 22 and 23 traverse across their respective rollers. By adjustment of the strips the degree of swivelling or rotational movement of the carriages around their guides can be regulated, this said swiveling or rotational movement being one of the movements necessary to enable the wheel to act on the back of the blade at its bolster end so that it is thicker than the back of the blade at its point.

To overcome the tendency of the wheel to rotate the sleeve 7 around the housing 6, the sleeve is slidably but non-rotatably mounted over the housing 6.

The mechanism for raising or lowering the sleeve 7, and so causing the blades to be brought up against or carried away from the wheel, will now be described.

A roller 30 revolves around a fixed pin held in a support 31 fastened to the bed of the machine.

A hollow lug 32 is provided exteriorly on the periphery of the sleeve 7 and has a plain bore. Located loosely in this lug is a threaded spindle 33, the lower end of which terminates in a housing 34, containing a pin and a roller 35. The spindle has a slot throughout its length, a fixed pin 37 attached to the lug engaging said slot, thereby permitting a sliding but not a rotary motion of said spindle.

The lower end of the lug 32 rests upon the upper face of an internally threaded worm wheel 38 surrounding the threaded spindle 33, a worm 39 engaging the said wheel.

The worm 39 can be operated by hand through the medium of a conveniently situated hand wheel and shaft in order to traverse the worm

wheel over the spindle 33 for the purpose of raising the sleeve 7 to suit the wear of the wheel 1.

A wedge 40 passes between the rollers 35 and 30 and supports the spindle 33, said wedge being connected at one end to a piston rod 41 of a piston 42 operating in a fluid cylinder 43.

Motive fluid is applied alternately to each side of the piston 42 in order to reciprocate the wedge 40 and cause the sleeve 7 and its attachments to rise or fall. The lower face of the wedge is parallel with the axis of the piston and piston-rod.

Part of the top face of the wedge is inclined, the remaining part being parallel to the bottom face of the wedge. During the grinding or polishing operation the rollers, 30, 35, bear on the parallel faces of the wedge as shown in Fig. 1C, and in this position there is no horizontal component of force tending to move the wedge, and therefore no tendency to raise or lower the sleeve 7.

A sprocket 44 is fastened to the face of one of the gear wheels 14, said sprocket being connected by means of a roller chain 45 to another sprocket 46. Sprocket 46 is supported by an extension 47 from the sleeve 7. Valve assemblies V¹ and V² are also supported by sleeve 7, and are for the purpose of controlling fluid to and from the cylinder 43 when the cylinders have reached their limits of reciprocation.

An extension 48 from the lifting wedge 40 carries three pins, 50, 51 and 52. Pins 50 and 51 operate the trip lever 49 of a reversing piston valve 56 in valve assembly V³, and pin 52 operates the lever 53 operating the cut-off piston valve 68 in valve assembly V³. The levers 49 and 99 have a quick action mechanism of any known construction.

Motive fluid, for example oil, is supplied to the machine by the pump 5 driven from the shaft 2, said pump obtaining its feed as from a sump reservoir 93 which may be contained in the base of the machine. The motive fluid is forced through pipe 54 and port 55 in the valve assembly V³ to the cut-off chamber containing piston valve 68. When piston valve 68 is in its left hand position (Figs. 1C and 5) the motive fluid passes through port 78 into the reversing valve chamber containing piston valve 56. Valve 56 controls primarily the admission of fluid to one or the other side of the pistons 10 in cylinders 11, and the exhaust from the opposite side of said pistons, as the case may be.

A lead 57 from valve assembly V³ engages header 61 and a branch 58 from this lead is connected to valve assembly V¹. As many branch leads 59 as there are cylinders are taken from the header 61. Each branch lead is attached to the hub end of a guide 9, there being one said lead to each guide.

Bores 60 in guides 9 carry the motive fluid to, or exhaust it from, the outer sides of pistons 10.

A lead 62 from valve assembly V³ engages header 63, and a branch 96 from this lead is connected to the valve assembly V². As many branch leads 64 as there are cylinders are taken from this header. Each branch lead is also attached to the hub end of a guide 9, again there being one said lead to each guide.

Bores 65 carry the motive fluid to, or exhaust it from, the inner sides of pistons 10.

Leads 129 are taken from the cylinders at position 66, where the leads 129 are always open

to the fluid movement to or from the inner sides of the pistons 10. Each said lead 129 is connected to its respective cylinder 67 of the automatic blade locating assembly.

- 5 Cut-off piston valve 68 is actuated by cam 69. A ring ratchet 70 is fastened on the face of the said cam. The cam and ratchet revolve on pin 71, which is supported at one end by a bracket 72 fastened to the bed of the machine. Lever 10 53 also has the pin 71 for a pivot and carries a pawl 73 fitted with a spring 74. The ratchet has say nine teeth corresponding with the number of blades which each holder is adapted to carry as hereinafter described.
- 15 When pulled to its left hand limit the extension 48 of the wedge 40 engages the lever 53 by means of the pin 52 and causes the pawl 73 to rotate the ratchet and the cam through a predetermined distance and in a counter-clockwise 20 direction.

When the wedge is pushed to its right-hand limit a spring 75 pulls back the lever 53 and pawl 73 against the stop 76, the spring and stop being fastened on an extension from a fixed 25 bracket 72. The cam edge is concentric up to a point 77 where the edge takes a radial drop. During the time the stem of piston-valve 68 is in contact with the concentric edge of the cam, the valve is in its lefthand position, thereby 30 allowing the motive fluid through port 55 from pump 5 to pass through port 78 but being prevented from exhausting through port 79 by disc 80 of piston valve 68.

Upon the wedge being moved to the left the 35 required number of times (equal to the number of blades on each blade holder 103) the point 77 is brought opposite the piston valve stem 68. Spring 81 then pushes valve 68 to the right, disc 80 uncovering port 79 to the motive fluid. 40 Port 78 is still open to the motive fluid, but the fluid follows the line of least resistance and exhausts back to the sump through pipe 193.

The valve chamber enclosing piston valve 56 has the one inlet port 78 from the cut-off chamber, two exhaust ports 82 and 83, and two outlet 45 ports 84 and 85.

The chamber of piston valve 100 has one inlet port 86, one outlet port 87 and one exhaust port 88.

50 The chamber of piston valve 101 also has one inlet port 89, one outlet port 90, and one exhaust port 91. The piston valves 68, 56, 100 and 101 are, in the main, of similar construction consisting of two spaced discs, 92 and 102 joined by 55 a neck, and having a stem 95 all as shown in connection with the piston valve 56, Fig. 5. The stem ends of the piston valves 56, 100 and 101 are threaded to suit the spools 93 which engage the trip levers 49 and 99. The stem end of piston valve 68 has a plain face for contact with 60 the edge of cam 69.

The distribution and action of the motive fluid will now be indicated, the machine being in the position shown in Figs. 1A, 1B and 1C 65 and the blades just entering on their outward working strokes:—motive fluid from pump 5 passes through ports 55, 78 and 85 in valve assembly V³, lead 57, header 61, leads 59 and bores 60, to the outer ends of pistons 10. The 70 cylinders, together with the blades on blade-holding sleeves or carriers 103, move outward along their respective guides. The blades are now being ground or polished. Lead 57 has a branch 58 to valve assembly V¹, but disc 97 obstructs the supply of motive fluid through port 75

87 to the right-hand end of cylinder 43, and the wedge remains stationary, keeping the blades 200 held up to and against the wheel.

As the blades are being acted upon by the wheel 1, the gear wheels 14 and the sprocket wheels 44 effect the rotation of sprocket wheel 43 so that when the grinding or polishing stroke is complete, adjustable catch 98 on sprocket 46 pushes the lever 99 to the left, causing the piston valves 100 and 101 to move to the left. This allows the motive fluid, previously cut off from cylinder 43, to force the piston 42, also the wedge 40 to the left, thereby allowing sleeve 7 and the blade carriers to drop away from the wheel. As the piston 42 moves to the left, the fluid in the cylinder to the left of the piston flows to exhaust through ports 90 and 91 in valve assembly V².

When the wedge has reached a predetermined point in this said stroke to the left, pin 51 pushes lever 49 to the left, causing the reversing piston valve 56 to move to the left, and causing a reversal of the flows of fluid to the two sides or faces of the pistons 10 of the cylinders 11.

In valve assembly V³ the motive fluid is now cut off from its previous outlet by disc 102 and passes through port 84, lead 62, header 63, leads 64 and bores 65 to the inner sides of pistons 10, causing the cylinders to move inward on their idle stroke. Branch 96 from lead 62 leads to 100 valve assembly V² but disc 105 cuts off the fluid supply to the left hand end of cylinder 43. The blades therefore remain clear of the wheel during the inward idle stroke of cylinders.

During this said inward stroke of the cylinders 110 the motive fluid flows through pipe 129 to the cylinder 67 and operates the turning and locating assembly, hereinafter fully described, thereby causing blade holder sleeve 103 to locate an unground or unpolished blade into position for 115 grinding.

During the inward movement of the cylinders 11 the sprocket wheel 46 is turned in the reverse direction and when the cylinders have reached a position where the wheel 1 is in line with the 120 bolster ends of the blades, the catch 104 on sprocket wheel 46 pushes lever 99 to the right, thereby allowing the motive fluid previously cut off from the left hand end of cylinder 43, by disc 105 obstructing the flow of motive fluid to 125 port 90, to force piston 42 and wedge 40 to the right, thereby lifting the blades into contact with the grinding wheel. When the wedge has reached a predetermined point in this said stroke, pin 50 pushes lever 49 to the right, causing the piston valve 56 to move to the right, thereby completing the cycle of operations.

With the piston valve 56 moved to the right as shown in Fig. 5 the motive fluid is being supplied through port 85 to the outer sides of the 130 pistons 10 and the cylinders are moving outwards. The fluid on the inner sides of the pistons is exhausting through bores 65 leads 64, header 63, lead 62, port 84 and exhaust port 83 back to the fluid sump through pipe 194. Fluid 140 from cylinder 67 of the turning and locating assembly is also exhausting along the same path. When the cylinders 11 reach their outward limiting positions and piston valves 100 and 101 have moved to the left, the fluid supply entering 145 the right hand end of cylinder 43 forces the piston 42 to drive the fluid out of the left hand end of the cylinder through pipe 195, port 90 and exhaust port 91 of valve assembly V² to the 150 fluid sump 93.

When the wedge 40 and thereby the piston valve 56 is pushed to the left, the motive fluid is being fed through port 84 to the inner sides of the pistons 10, and the fluid at the outer sides of the pistons is now exhausting through bore 60, leads 59, header 61, lead 57, port 85 and exhaust port 82 back to the fluid sump 93 through the pipe 193.

When the cylinders have reached their inward limiting positions, and piston valves 100 and 101 have moved to the right to the position shown in Fig. 5 the fluid supply entering the left hand end of cylinder 43 forces the piston 42 to drive the fluid out of the right hand end of the cylinder through pipe 196, port 87, and exhaust port 88 of the valve assembly V¹ back to the fluid sump through the pipe 197.

The speed of the inward idle stroke of the cylinders is roughly twice that of the outward working stroke, and is proportional to the effective area of the outer sides of the pistons 10, and the effective area of the inner sides of these pistons.

One of the turning and locating assemblies for the blade carriers will now be described:—A live spindle 106 within each carrier 103 has at its outermost end a screw thread on which is locked a hand wheel 107 and at its innermost end has a further screw thread on which is locked the carrier or blade holding sleeve 103 which has say nine supports for blades.

Surrounding the spindle 106 is a hollow shaft 103 which is held securely by bracket 109 from cylinder 11 so that the shaft 103 is held in a radial position relatively to the grinding wheel and is parallel or substantially parallel to the axis of the cylinder 11. The right hand end of shaft 108 acts as a bearing support for the movable blade-holding sleeve 103. The left hand end of shaft 108 has a flanged collar 110 fastened to it.

The collar 110 supports the case 111 integral with which is the fluid cylinder 67. A ring 112 is fastened concentrically to the face of the collar 110. The outer face of the ring 112 is in the form of one half 113 of a dog clutch, and this ring also carries two cam surfaces 114 arranged diametrically opposite, the inclination terminating in a perpendicular return 115.

50 A ring ratchet 116 fixed to the spindle 106 carries the other half 117 of the dog clutch. An armed sleeve 118 is a working fit on the spindle 106, side play being eliminated by a nut 119 screwed on spindle 106.

55 One end of the armed sleeve has three arms or extensions shrouding the ratchet 116. Two of these extensions 120 are diametrically opposite, the other extension 121 being at right angles to the said two extensions 120. Extension 60 121 carries a pawl 122 which engages the teeth on ratchet 116. A finger 123 pivoted on a pin 124 has a short rearward extension 133, the finger being in contact with the cam surfaces 114. A fixed pin 125 acts as a stop for the short extension and a compression spring 126 tends to keep the extension on to the stop.

The other or outer end of the armed sleeve has most of its perimeter toothed at 127, Fig. 1A and 4. Engaging these teeth is a rack milled on the piston 128 working in the cylinder 67. Motive fluid is supplied to the cylinder 67 by the lead 129 from points 66 on the cylinders 11. A spring 130 (Fig. 4) nesting in a bore in piston 128, forces the piston back to its initial position when the motive fluid is released to exhaust.

The cylinder ends act as piston stroke limits. On that portion of the spindle 106 extending through a bore in the casing 111, is a declutching collar 130, the collar having a cam face 131 corresponding to a face on the boss of casing 111, the collar being fitted with a lever arm 199 whereby it may be operated by hand to effect declutching of the dog clutch when it is desired to turn the blade carrier by aid of the wheel 107 for any reason such as charging the carrier independently of the automatic turning effected by the machine.

The number of ratchet teeth and the number of dogs on the part 116 is the same as the number of blade supports on the sleeve 103, say 90 nine: therefore the ratchet teeth would be say 40° apart. The stroke of the piston 128 is regulated so that the pawl swings through an angle of about 70° therefore giving an idle swing of 30° over and above the pitch of the 95 ratchet teeth.

When the cylinders 11 are on their inward strokes, the motive fluid through pipe 129 forces the piston 128 along its cylinder, the armed sleeve rotates around the spindle 106, which is 100 now stationary, being locked by means of the dog clutch, and held locked by the spring 132. During the first 30° of rotation of the armed sleeve the pawl 122 passes idly down the back of a ratchet tooth (see Fig. 4) simultaneously 105 as the fingers 123 are travelling along the cams 114, causing the dogs 117 and 113 to be gradually declutched. When the 30° swing is finished the dogs 117 and 113 are out of mesh, dogs 117 having been pushed out of contact by the cams 110 pushing against the fingers 123, said fingers transmitting the push to the armed sleeve and thence to nut 119 and spindle 106.

The ratchet 116 and dogs 117, armed sleeve 121 and spindle 106 together with sleeve 103 115 and hand wheel 107 are now free to revolve. The pawl 122 is by now positively engaged with a ratchet tooth and the piston 128 has a remaining length of stroke equivalent to 40° rotation of the armed sleeve. The piston therefore turns 120 the armed sleeve, the pawl in this sleeve turns the ratchet ring 116 and dogs 117 until the piston reaches its limit of working stroke. Simultaneously the fingers 123 have overlapped the end 115 of the cams 114, and as the dogs are 125 now in line of mesh, the spring 132 pulls the said dogs into lock. As the blade holding sleeve 103, spindle 106 and the dogs 117 are fastened together, the sleeve 103 has also rotated 40° or 1/9th of a revolution. The sleeve holding say 130 nine equally spaced blades has therefore placed a fresh blade into grinding position.

The preceding movements occur on the inward stroke of the cylinders, when the carriers and cylinders are making their idle inward stroke. When the fluid supply is reversed by the action of the reversing piston valve 56, the cylinders 11 begin their working strokes, with the blades up against the wheel. As the motive fluid to cylinder 67 is now open to exhaust through the pipe 129, the spring 130 (Fig. 4) forces the piston 128 back to its initial position, the armed sleeve together with the pawl and the fingers, also returning to their initial position.

The blade-holding assembly and the method of changing the blades are as follows:—

A lever 134 working on a pin 139 held in bearing bracket 136 has a roller 137 attached to one end, the other end being an off set 138 at right 150

angles to the lever, said offset bearing down on the shank of a blade which is resting in a V-block 135 fastened in the sleeve 103. The face of the blade rests on its support which has a 5 base shaped to give the blade a firm bearing surface. A pin 140 forms a stop for the blade in its tendency to be moved with the sweep of the wheel. A spring 141 bearing on the lever 134 presses down the offset 138 to provide sufficient pressure on the blade shank or handle in 10 the V-block, to hold the blade whilst it is being ground.

A weaker spring 142 tends to throw the blade out of its holder. An arm 143, Figs. 1B and 3, 15 is pivoted on a pin 144 on the bracket 109 and is normally clear of the path of movement of the rollers 137. When the grinding operation is complete and the machine has come to a standstill this arm is turned inwards to the extent 20 permitted by a fixed pin 145 also on bracket 109 and the inner end of the arm is then in the path of the rollers 137 so that as the carriers or sleeves 103 are turned by hand (by the use of lever arm 199 and wheel 107 as previously 25 described) the rollers 137 come into contact with the arm and are pressed inwards as shown in Fig. 2. The offset 138 is thus removed from contact with the shank or handle and the blade or knife is thrown out of its holder by the spring 142. 30 The holder is thus cleared ready to receive a fresh unground blade which is inserted and held until the handle 107 has been turned sufficiently for the roller 137 to move on past the inner end of the arm 143, when the lever 134 35 is again operated on by the spring 141 to press the offset 138 down on to the shank or handle of the newly inserted blades. In this way each carrier can be charged with, say, nine, free blades.

40 The arm 143 is finally swung clear of the rollers 137, the declutching lever 199 is released, and the machine is then ready for a fresh grinding or polishing operation.

In the modification shown in Fig. 6 the shaft 45 2^o, as before, runs in a fixed sleeve 6^o and carries a metal disc 1^a with abrasive wheel 1^b. On this fixed sleeve slides an outer sleeve 7^c having no rotary motion around the fixed sleeve. Several, say, eight pistons 10^e and piston rods 50 9^e (henceforth called "rods") are attached by the inner ends of the rods to outer sleeve 7^c in such a manner that they converge radially. Around each rod is a knife-holding reciprocating cylinder 11^e (henceforth called "cylinder") 55 reciprocation along the rods being produced by the alternate admission and ejection of a fluid to and from the two sides of the piston on each fixed rod. Holders for blades 200^e are independently attached to the outside periphery of the 60 cylinders.

One complete reciprocation of each cylinder consists of an idle stroke (during which said stroke the faces of the said blades are forced inwards towards the centre line of shaft and 65 away from the working face of wheel) and a working stroke, during which the faces of the said blades are forced outward away from the centre line of the shaft and up against the working face of the wheel.

70 The movement of the blades, upwardly towards or downwardly away from the working face of the wheel, is directly effected by the movement of the sleeve 7 as it rises or falls. This movement of the sleeve may be accomplished by 75 means of a bell-crank lever so arranged that it

holds the outer sleeve (and therefore the knife blades) against the working face of the wheel during the working stroke, said lever being also instrumental in holding the outer sleeve away from the working face of the wheel during the 80 idle stroke.

The bell-crank lever may be actuated from a piston actuated by fluid, as for example, oil.

The machine is operated in a very similar way to that described with reference to Figs. 1-5, but in the present construction a two-way branch valve controlled by hand is introduced into the fluid system for the purpose of directing the fluid to alternate cylinders 11^e and cutting it off from the remaining cylinders, and then cutting off the fluid from the said remaining cylinders and directing it to the said alternate cylinders. During the time that alternate cylinders are making their working and idle strokes the remaining cylinders are at rest, and 90 the blades thereon can be changed.

Although the invention has been described more particularly as employing oil pressure it will be understood that the invention is not limited thereto. For example, other fluid pressure 100 such as air pressure might be used.

What I claim and desire to secure by Letters Patent is:

1. A machine for grinding or polishing cutlery comprising a rotary grinding or polishing wheel 105 mounted about a vertical axis, a plurality of radially disposed blade carrying members mounted below and in proximity to a lateral face of said wheel, means for effecting inward and outward movements of said blade carrying members radially with respect to the axis of said wheel, means for causing the blade carrying members to rise and contact blades thereon with the wheel on outward radial movement of said blade carrying members, means for causing the blade carrying members to fall again on inward radial movement, means for imparting a canting movement to the blade carrying members during their outward radial movement, and means for imparting a rotational movement to said blade 110 carrying members subsequent to their outward radial movement so as to effect an angular change of their position for their subsequent outward radial movement.

2. A machine for grinding or polishing cutlery, comprising a rotary grinding or polishing wheel mounted about a vertical axis, a plurality of radially disposed blade carrying members mounted below and in proximity to a lateral face of said wheel, fluid operated means for effecting 115 inward and outward movement of said blade carrying members radially with respect to the axis of said wheel, means for causing the blade carrying members to rise and contact blades thereon with the wheel on outward radial movement of said blade carrying members, means for causing the blade carrying members to fall again on inward radial movement, means for imparting a canting movement to the blade carrying members during their outward radial movement and means for imparting a rotational movement to said blade carrying members subsequent to their outward radial movement so as 120 to effect an angular change of their position for their subsequent outward radial movement.

3. A machine for grinding or polishing cutlery comprising a rotary grinding or polishing wheel mounted about a vertical axis, a plurality of radially disposed blade carrying members mounted below and in proximity to a curved 125

lateral face of said wheel, fluid operated means for effecting inward and outward movements of said blade carrying members substantially radially with respect to the axis of said wheel, fluid operated means for causing the blade carrying members to rise and contact blades thereon with the wheel on outward radial movement of said blade carrying members and to fall again for inward radial movement, means for imparting a canting movement to the blade carrying members during their outward radial movement, mechanically operated means for synchronizing the radial movement of the blade carrying members and hand operated means for raising said blade carrying members bodily towards the grinding or polishing wheel.

4. A machine for grinding or polishing cutlery comprising a rotary grinding or polishing wheel mounted about a vertical axis, a plurality of radially disposed blade carrying members mounted below and in proximity to a curved lateral face of said wheel, fluid operated means for effecting inward and outward movements of the alternately disposed blade carrying members substantially radially with respect to the axis of said wheel, fluid operated means for causing the blade carrying members to rise and contact blades thereon with the wheel on outward radial movement of said blade carrying members and to fall again for inward radial movement, means for imparting a canting movement to the blade carrying members during their outward radial movement, mechanically operated means

for synchronizing movement of the alternate blade carrying members and hand operated means for raising said alternate blade carrying members bodily towards the grinding or polishing wheel.

5. A machine for grinding or polishing cutlery comprising a rotary grinding or polishing wheel mounted about a vertical axis, a plurality of radially disposed blade carrying members mounted below and in proximity to a curved lateral face of said wheel, fluid operated means for effecting inward and outward movements of said blade carrying members substantially radially with respect to the axis of said wheel, fluid operated means for causing the blade carrying members to rise and contact blades thereon with the wheel on outward radial movement of said blade carrying members and to fall again for inward radial movement, means for imparting a canting movement to the blade carrying members during their outward radial movement, mechanically operated means for synchronizing the radial movement of the blade carrying members and hand operated means for raising said blade carrying members bodily towards the grinding or polishing wheel and means for imparting a rotational movement to said blade carrying members subsequent to their outward radial movement so as to effect an angular change of their position for their subsequent outward radial movement.
